UNITED STATES PATENT OFFICE.

CHESTER A. MORRISON, OF MANITOU, COLORADO.

WINDLASS.

SPECIFICATION forming part of Letters Patent No. 639,596, dated December 19, 1899.

Application filed January 8, 1898. Serial No. 666,060. (No model.)

To all whom it may concern:

Be it known that I, CHESTER A. MORRISON, a citizen of the United States, residing at Manitou, in the county of El Paso and State 5 of Colorado, have invented a new and useful Windlass for Mining Purposes, of which the following is a specification.

My invention relates to improvements in windlasses to be used in mining, in which the 10 windlass-drum and attachments can be speedily removed from the supporting-standards. The objects of my improvements are, first, to provide ball-bearing journals for the windlass-drum and its actuating means; second, 15 to facilitate the speedy removal of the windlass-drum and its actuating means from the supporting-standards; third, to provide a journal-box for the shaft of a windlass-drum, which journal-box will also serve as a journal- 20 for the drum-actuating machinery and as a support and journal for the pawl used in connection with such windlass-drum; fourth, to afford facilities for securing a ratchet to each 25 end of the windlass-drum, and, fifth, to provide a shaft for use in a windlass, which will be secured against longitudinal movement without the use of collars or similar means. I attain these objects by the mechanism illustrated in the accompanying drawings, in 30 which—

Figure 1 is a side view of the entire windlass. Fig. 2 is an end view. Fig. 3 is a sectional end view of the journal-box, taken through the dotted line 1 2 in Fig. 1. Fig. 4 is an 35 edge view of the ratchet-wheel, showing the collar and hub attached to it. Fig. 5 is a side view of the plate for holding steel balls against the cap D. Fig. 6 is a longitudinal view of the shaft to which the crank G and 40 pinion F are secured, showing the grooves for ball-bearings. Fig. 7 is a portion of the drum-shaft, showing the groove for the ball-bearing.

Similar letters refer to similar parts throughout the several views.

The windlass and its actuating mechanism are supported by two heavy wooden standards I I, secured by any suitable means to the curbing of the shaft. On the top of these 50 standards rest the peculiarly-constructed metal caps D, as fully appears from the sectional view as shown in Fig. 3. These caps

rest loosely on the top of the standards, so that they can be readily removed vertically. The upper portion of the cap D serves as a 55 base of a journal-box for the shaft e, while from the center there is a downward-projecting portion which serves as a bearing for the shaft L. The cap D has an arm C on one side, which serves as a journal for the short 60 shaft f on which the pawl C rotates. The journal-cap d is secured to the cap D by means of the threaded bolts d'. There is a groove in the center of the journal-cap d and a corresponding groove in the cap D to receive 65 steel balls to form a bearing for the shaft e, and the shaft e has a similar groove e' to receive the balls. The groove e' in the shaft serves the important purpose of keeping the shaft from moving longitudinally, 70 thus dispensing with a collar at either side of the journal-box and the friction which would result from the collar coming in contact with the box.

In order to provide the short shaft L with 75 ball-bearings, provision is made for placing steel balls at each side of the cap D where the shaft passes through said cap, and the shaft is grooved, as shown in Fig. 6 at l, at the point where the shaft rests upon the balls to 80 keep it from longitudinal movement. The cap D is beveled around the hole through which the shaft L passes at either side, and a plate h, similarly beveled, is secured to the cap D by means of bolts or other suitable 85 means, and the two beveled edges form a race-way in which the steel balls run, thus forming a ball-bearing at each side of the cap D for the shaft L.

The plate h, as shown in Fig. 5, has the 90 perforations h' to receive the bolts that secure it to the cap D and short square lugs h², that fit in sockets in the cap D to keep the plate from rotating and that assist in supporting the weight-pressure of the shaft against 95 the balls when the windlass is in operation. If it were not for these square lugs, the small bolts through the perforations h' would have to support the plates and the pressure of the shaft on the balls in the sheave; but by using 100 lugs on the plate the weight falls on them and not on the bolts, thus making a strong and durable support for the plates. The plates are beveled around the edge of the hole

through which the shaft passes, as shown by h^3 , and the cap D is similarly beveled on each of its sides around the hole through which passes the shaft L.

5 The shaft L has a pinion F secured to it by a key, and its outer end is made square to receive the crank G, which is kept on the shaft by means of the threaded nut g, which is run up against the hub on the crank. The pinion F may be of any desired size, preferably one-half the diameter of the cog-gear E, so that two revolutions of the crank will be required to make one revolution of the drum of the windlass.

15 The shaft e has secured to its outer end the cog-gear E. This shaft after passing through the cap D extends through an inner hub b^2 in the ratchet-wheel and into, but not through, the drum A. A pin b^3 , which passes through 20 the hub b^2 and through the shaft e, keeps the shaft from turning in the hub and causes the shaft and ratchet-wheel to rotate in unison.

The ratchet-wheel B is cast with a broad heavy collar b on one side of it and a hub b^2 25 in the center. The collar slips over the end of the drum, while the hub is forced into the center of the drum A. The ratchet-wheel B is cast solid, with three or more holes through it to receive long wood-screws B^2 B^3 , which 30 enter the head of the drum and keep the shaft e and the ratchet-wheel from turning in the drum. The ratchet-wheel is constructed with the hub, collar, and screws through it and fastened to the shaft e and then attached to the 35 drum. By this means the shaft e is given all needed strength without passing through the drum its entire length.

The drum A has heavy iron bands a on each end to prevent it from cracking or splitting.

40 A pawl C, rotating on the short shaft f, is so constructed that it engages the teeth on the ratchet-wheel when the operator wishes to secure the bucket elevated by the windlass from falling accidentally. When not in use, the pawl can be thrown back out of engaging contact with the ratchet-wheel.

All the parts described are made in duplicate, and in a complete windlass one set is secured to each end of the drum in the manner above indicated, so that the windlass can be operated from either end with like results.

The standards I I have a deep square socket in their upper portion to fit the cap D.

55 In use the caps D D, having secured in them the shafts L L, to which are attached the pawls C C, are permanently fastened to the shafts e e by means of the box-caps d d and the screws d' d', so that the drum A,

ratchet-wheels B B, cog-gears E E, pinions F F, cranks G G, and pawls C C will be attached together, whereby all these parts can be removed from the supporting-standards in connection with the drum when a blast is fired in the shaft below the windlass.

In operation the caps D D, to which are connected the drum and its actuating means and the two reversely-set ratchets, with their pawls, are slipped down over the supporting-standards I I until they rest securely on the top thereof. A rope, with a bucket attached to each end, is wound around the drum a number of times, so that one bucket will be elevated while the other descends. The operator takes hold of the crank at the end of the 75 drum where the bucket will ascend, throws the pawl into engaging contact with the ratchet-wheel, and by turning the crank rotates the pinion F, which engages the cog-gear E, causing it, the shaft e, and the drum 80 and ratchets to revolve. The pawl secures the bucket from accidental descent and holds the bucket when it has reached the surface until the operator can remove it to the dump.

When a blast is to be fired in the shaft, the 85 drum is lifted vertically until the caps D D are free from the standards, when it and all its actuating machinery are removed together to a place of safety. After the blast the windlass is returned, the caps slipped down over 90 the standards, and the windlass is ready for immediate use. There is no danger of losing the steel balls which form the bearings of the different shafts in the operation of removing and returning the drum, while the long flanges 95 on the caps D D furnish a steady and safe means of keeping the windlass firm when in operation. The pinions F F being directly beneath the cog-gears E E and in the center of the supporting-standards there is no side 100 draft on the caps.

Having described my invention, what I claim as new, and desire to secure by Letters Patent, is—

The combination in a windlass of the removable cap D and the journal-cap d secured thereon, the drum A, the shaft e journaled in said cap D and passing into the drum A, the ratchet-wheel B secured to the shaft e and the drum A, the pawl C pivoted on the cap D and adapted to engage the ratchet-wheel, the pinion E on the outer end of the shaft e, and means for operating said pinion, substantially as described.

CHESTER A. MORRISON.
